SUCTION CLEANER

Bernard C. Becker, Canton, Ohio, assignor to The Hoover Company, North Canton, Ohio, a corporation of Ohio

Application August 23, 1937, Serial No. 160,399

7 Claims. (Cl. 15—9)

This invention relates to improvements in suction cleaners of the type adapted to be converted to and from off-the-floor cleaning operations through a hose and cleaning tools and further characterized by the presence of a rotary agitator in the nozzle which acts to beat the carpet during normal cleaning operation.

When an agitator equipped cleaner is operating with dusting tools, the agitator serves no useful purpose, and for this and other reasons which need not be enlarged upon, it is the common practice to provide means for automatically raising the nozzle portion of the cleaner to a predetermined height above the carpet surface and preferably by adjusting either the front or rear wheels vertically and in such a way that the dusting tool hose or converter cannot be attached without the accompanying lifting of the agitator out of contact with the carpet surface. One arrangement for accomplishing this result includes a hinged bracket supporting the rear wheels and a barrier member normally positioned to obstruct the entrance to the converter port, so that it is necessary to first depress the rear end portion of the cleaner and raise the agitator before the barrier member is shifted from its obstructed position to permit the insertion of the converter member.

An inter-related nozzle adjustment and converter arrangement of this type is disclosed in Patent 2,142,810, and the object of the present invention is to provide an improved nozzle adjusting and converter port barrier mechanism, more compact and workmanlike in design and superior from an operating standpoint in that the barrier member also serves to lock the converter member in its converting position.

And another object of the present invention is to provide a somewhat improved design for the converter member per se and also for the port which receives the converter member with a slight rocking movement just before it finds its seat. And in this connection, a converter member of the so-called rocking type, has also been disclosed in an earlier application, filed June 25, 1936 and bearing Serial No. 87,162, and having somewhat the same purpose and design, although with one essential difference, namely, that in the earlier disclosure the rocking movement of the converter member serves to impart a cam action for actuating a nozzle elevating mechanism, whereas in the present disclosure (and this is also true of the earlier disclosure in Patent 2,142,810, above mentioned) the agitator is lifted out of contact with the carpet surface by the op-

erator tilting the cleaner bodily on its front wheels either by the pressure of the hand or foot.

Other improved features of construction and design will be brought out in the discussion in connection with the accompanying drawings, in which:

Figure 1 is a view in side elevation of a suction cleaner embodying the improved features, with details of the nozzle adjusting mechanism shown in vertical section as taken on line 1—1 of Figure 2;

Figure 2 is a bottom plan view of the cleaner with a portion of the bottom wall of the passage leading to the fan chamber broken away to show the internal arrangement;

Figure 3 is a view in side elevation similar to Fig. 1 and showing the cleaner body tilted, the nozzle raised and the converter member inserted and locked in converting position.

Figure 4 is a fragmentary bottom plan view of the cleaner with that portion immediately adjacent the converter port in horizontal section as taken on line 4—4 of Figure 3;

Figure 5 is a detailed view in vertical section taken on line 5—5 of Figure 4, showing the converter member in converting position.

Figure 6 is a perspective view of the converter member and

Figure 7 is a perspective view of the combined barrier and converter locking member as it appears when removed.

The suction cleaner herein disclosed follows generally the standard design, consisting of a main casing 1 having a nozzle 2 at its forward end and from whence the sides of the casing 1 converge with a slight curvature toward its rear end where is located an outlet connection 3 to which a removable dirt bag 4 is attached. Centrally of the main casing 1 is the fan chamber 5, generally circular in shape and communicating with the outlet connection 3 by means of a rearwardly extending passage 5a.

Within the fan chamber 5 is mounted a suction fan 6 rotative about a vertical axis and driven by a motor supported upon the casing 1 and enclosed within a separate casing 7.

Located at the center of the bottom wall of the fan chamber 5 and concentric with the vertical axis of the fan, is a circular inlet opening 8 to the fan chamber, usually referred to as the "fan eye". The fan chamber is connected with the space enclosed by the nozzle portion 2 of the casing 1 by an air passage formed by a shallow wall 9 depending from the bottom wall of the fan chamber 5 and enclosing the two sides and rear

end portion of the passage around the fan eye 8, and a removable bottom plate 10 fitting over the space enclosed by the side wall 9.

Extending lengthwise of the nozzle and immediately above the nozzle mouth 11, is the rotary agitator 12 consisting of a cylindric metal shell having an arrangement of longitudinally extending beater bars 12^a and brushes 12^b, which project a fraction of an inch beyond the plane of the nozzle mouth. The agitator is driven by a belt 13 extending through the air passage from the nozzle chamber to a pulley 14 at the lower end of an axial extension of the hub of the fan 6.

The body of the cleaner is supported upon pairs of wheels located near the front and rear ends of the main casing 1. The front wheels 15, 15 are journaled on fixed bearings 16, 16 located just rearwardly and inwardly from the ends of the nozzle. The rear wheels 17, 17 are located just forwardly of the outlet connection 3 from the fan chamber and are journaled at the ends of a relatively short axle 18, forming a part of a unitary rear caster assembly which will now be described in detail:

Extending transversely beneath the main casing 1 is a hollow beam 19 journaled for limited rocking movement upon a bearing shaft 20 passing lengthwise through the beam 19 and supported at its outer ends by a pair of vertical arms 21, 21 formed integral with the bottom wall of the casing 1 and extending a short distance below the under side of the fan casing 5. This beam 19 is symmetrically arranged with respect to the center line of the cleaner body and at its central portion is an integral bracket 22 extending radially in a general rearward and downward direction and consisting of a pair of spaced arms supporting the axle 18 just inwardly from the rear wheels 17—17. Enclosed within the hollow beam 19 is a plurality of torsion springs 23, one of said springs being located in each of several compartments into which the beam is preferably divided longitudinally by transverse webs 19^a (Figure 2). The springs are coiled around the bearing shaft 20, each having one end suitably anchored against the underside of the relatively stationary casing 1 and the other end exerting pressure upon the beam at a point offset from its axis and in a direction to rotate the beam counterclockwise on its supporting shaft, that is, in a direction to raise the rear portion of the cleaner body upwardly and tilt the nozzle portion downwardly when the weight of the cleaner is supported by the wheels in contact with the floor surface.

Now, mounted at one end of the beam 19 and forming an integral part thereof is a plate-like member which forms the combined barrier and converter locking lever 24 shown in Fig. 7. This lever is secured flatwise against the end face of the beam and is rigidly secured thereto by means of a bolt 25 passing through the central portion of the lever and a radial arm 19^b formed integral with the beam 19. The lever arm 24 also has bearing support upon the shaft 20 about which it rotates with the beam 19 and projects in a general forward direction and substantially in alignment with the rear wheel carrying bracket 22 as shown in Figure 1.

And finally, the lever arm 24 is located at the end of the beam 19 adjacent the converter port side of the cleaner, in fact, the forwardly projecting arm of the lever is positioned to swing in a limited arc in a vertical plane traversing

the passage way from the converter port into the space surrounding the fan eye 8.

As clearly shown in Figures 2 and 4, the converter port is arranged substantially at right angles to the longitudinal center line of the cleaner body and directly beneath the bottom wall of the casing 1, being defined in part by depending wall segments 26, 26, flanking the entrance to the port and another pair 27, 27 marking the entrance into the inlet passage from the fan chamber and forming the supports for supporting a hinged gate or valve member 28, normally held in vertical and closed position by a torsion spring 29. A bottom wall section 30 of sheet metal completes the converter port, being generally L-shaped in cross section and anchored at its four corners by means of screws 31. A section of the bottom plate 30 is cut out at 30^a to form a slot through which the lever arm 24 may enter the passage from below in its rocking movement as a part of the rear caster assembly.

At the forward end of the lever arm 24 are two upwardly facing detents 24^a and 24^b, the innermost detent 24^b being spaced slightly above the outer and both having relatively wide contact faces formed by bending their edges over in L-shape. And immediately beyond the detents 24^a and 24^b is a laterally projecting lug 24^c formed by stamping a rectangular section from the plate and bending it outwardly at right angles. As shown in Figure 1, this lug 24^c is positioned immediately above the bolt 25 which anchors the lever arm to its support.

Now, bearing in mind that the rear caster assembly is constantly under the tension exerted by the torsion springs 23 tending to lift the rear end of the cleaner body and tilt the nozzle downwardly, it follows that without some adjusting means the body of the cleaner would remain in this tilted position except when sufficient force was applied to the rear end portion thereof to overcome the spring tension. Such an adjustment is provided in the form of a hand-manipulated adjusting screw 32 having a knob 32^a projecting above the top surface of the casing 1 at one side of the motor cover 7. The screw regulates a vertically adjustable nut 33 engaged by a threaded stem at the lower end of the screw, the latter being rotatively supported by a bracket 34 fixed to the casing 1. As thus mounted, the knob 32^a may be turned in either direction to shift the nut 33 upwardly or downwardly in vertical guideways provided for its support.

As clearly shown in Figures 1 and 3, the traveling nut 33 of the adjusting device is positioned immediately above the laterally projecting lug 24^c of the lever arm 24, which forms a stop member adapted to contact the adjustable nut 33 and thus limit the swinging movement of the lever arm 24 in an upwardly or counter clockwise direction. However, it will be observed that there is no positive connection between the adjusting nut 33 and the lever arm 24 so that the body of the cleaner is always free to tilt about the front wheels upon depressing the rear end. Thus in Figure 1, the body of the cleaner is maintained at a constant nozzle height by the position of the adjusting nut 33, although this adjustment may be varied either to raise or lower the nozzle by turning the adjusting screw 32 in one direction or the other. Beyond this no variation in the nozzle height will take place unless sufficient pressure is applied at the rear portion 75

of the cleaner body to depress the same and overcome the tension of the torsion springs 23.

Thus, while the cleaner is being operated at the nozzle height adjustment determined by regulating the adjusting screw 32, the forward end of the lever arm 24 projects into the converter passageway and definitely prevents the insertion of a converter member therein. But, as clearly shown in Figure 3, by pressing downwardly on the rear end portion of the cleaner it is possible to tilt the nozzle upwardly and at the same time rock the body of the cleaner on rear caster assembly until the lever arm 24 is shifted below and out of obstructing position in the converter passage. Now, while the cleaner body is in its tilted position, it is possible to insert the converter member 35 into its port and thence into converting position without interference from the barrier lever 24.

As clearly shown in Figure 6, the converter member 35 is a tubular fitting adapted to be attached at the end of a dusting tool hose, being generally cylindric in shape at its attaching end but reduced to a comparatively narrow blade with flat top and bottom faces throughout its outer end portion.

As hereinbefore stated, the converter member together with the converter port are generally of the type shown in the earlier disclosures hereinbefore mentioned and therefore it is proposed not to discuss the converter arrangement in detail except insofar as it may embody improved features of design or function.

Since the end portion of the converter member 35 is flattened on two sides and the converter port is shaped to correspond, the former is intended to be inserted with the concave side of the hooked shaped end portion facing toward the belt pulley 14 as clearly shown in Figure 4. Now, in order to insure the converter member being properly presented and inserted into the converter port and, having been inserted to impart a limited but definite rocking movement thereto as it finds its seat, there are formed along the front and rear edges of the converter member a group of cam projections or indentations (as the case may be) which will now be identified:

Beginning at the inner end of the converter member (Fig. 6), there is a pointed cam 36 with sloping sides projecting from its rearwardly facing side edge. Then immediately forward of the cam 36 is an inclined shoulder 37 facing toward the inner or cylindric end of the converter member, and, which as will later be pointed out, coacts with the detent 24b of the lever arm 24 to lock the converter member in converting position. And, just forwardly of the shoulder 37 and on the same edge of the converter member is a curved recess or indentation 38 serving as a positioning boss for the converter member when it reaches its final converting position, as will presently be explained.

On the opposite or forward edge of the converter member (Fig. 4) is an elongated arcuate cam 39 extending lengthwise substantially throughout its flattened mid-section and somewhat wedge-shape in cross-section. And finally, projecting downwardly from the underside of the cam 39 midway of its ends is a pointed lug 40 with its end projecting beyond the flattened bottom face of the converter member and having an upright shoulder facing toward the extreme end of the converter member. The purpose of this lug will presently be seen.

It will be understood that the movement of

the converter member into converting position is generally endwise, it being only necessary for the operator to present the converter to the entrance of the converter port and then to push inwardly, whereupon the several cams act to impart a rocking movement to the converter member as it approaches its final position, in order that it may clear the pulley 14 which otherwise would interfere with its proper seating across the inlet passage to the fan chamber.

The operation of converting the cleaner for off-the-floor cleaning operation will now be described: For normal carpet cleaning operation, the cleaner is adjusted to the proper nozzle height by the adjusting screw 32 in the manner already set forth, the adjusting mechanism preferably including a visual height indicator consisting of an L-shaped arm 42 rigidly fixed to the beam 19 of the rear caster assembly just inwardly from the end which carries the barrier lever arm 24. This indicator arm extends in a general upwardly and rearwardly direction, its outer end portion having the form of an arcuate sector, positioned directly beneath and in alignment with an opening or window 43 in the top wall of the casing 1. The quadrant 42a has a flat upwardly facing surface on which suitable nozzle height indications are stamped, such as H, M and L, standing for "High", "Medium" and "Low", respectively, and obviously having reference to the different heights to which the nozzle may be adjusted.

Assuming now, that it is desired to attach the dusting tool hose for operation with the dusting tools, it is first necessary to clear the obstruction from the entrance to the converter port and this is done by pressing downwardly on the rear end of the cleaner body, the most convenient way being to press down with one hand while holding the converter in the other in readiness to force it into the port as soon as the barrier lever 24 has been removed. As already explained, the depression of the rear portion of the cleaner body simultaneously raises the nozzle and removes the barrier arm 24 from port obstructing position. The converter member 35 may now be inserted, but as already explained it must enter the converter port in the proper way, namely, with the edge bearing the cam projection 36, the shoulder 37 and the cam recess 38 facing rearwardly as shown in Figure 4. And in order to prevent the converter member from being inserted in any but the proper way, a shallow groove 44 is provided along the forward edge of the bottom plate 30 of the converter passage and positioned to register with the lug 40 projecting below the bottom face of the converter member, so that unless the same enters the converter port properly, the lug 40 would strike the top edge of the port entrance, preventing further progress and thus making it necessary to reverse the converter member so that it can be properly inserted. Having inserted the converter member into the port, it is then only necessary to force the same inwardly, the direction of movement being in a straight line until it reaches the dotted line position shown in Figure 4, namely, just in advance of its final position with its forward end seating over the front half of the fan eye and just ahead of the belt pulley.

Now, on reaching that dotted line position it will be observed that contact takes place between the forward sloping edge of the cam 39 along the front face of the converter member with a rounded vertical abutment edge 45 near the forward and inner end of the converter port,

- and at the same time, the forward sloping edge of the pointed cam 38 near the outer end of the converter member comes into contact with an inclined abutment face 46 at the entrance to the converter port. With contact at these two points momentarily retarding the endwise movement of the converter member, it follows that by the ensuing cam action, the converter member is shifted or rocked forwardly through a small arc 5 and at the same time is finally brought into its converting position as indicated by full lines in Figure 4, (with the cam recess 38 near the forward end of the converter member registering with a correspondingly convex seat 47 at the inner end of the converter passage and just short of the hinged gate member 28, which has been swung downwardly into open position against the bottom plate 10 as clearly shown in Figure 5).
- 20 Once the converter member has been inserted into its port, it is no longer necessary to hold down the rear end of the cleaner inasmuch as the detent 24a at the forward end of the barrier lever 24 contacts the underside of the converter member as clearly shown in Figure 3, and holds the cleaner in its nozzle raised position. And finally, with the converter member in position, the shoulder 37 is engaged by the locking detent 24b on the barrier lever, thus bringing about a 25 locking connection which holds the converter member to its seat and prevents its withdrawal by a direct pull on the hose as may frequently occur during cleaning operations.
- Upon completing the off-the-floor cleaning 30 operation, the cleaner is restored to its operating condition, merely by pressing down slightly on the rear portion of the cleaner, thus releasing the converter member so that it can be withdrawn from its port, whereupon the cleaner is restored to its proper nozzle height adjustment 35 as determined by the manual adjusting device.
- Having set forth the preferred embodiment of my invention, I claim:
1. In a suction cleaner, the combination of a 40 casing including suction-creating means, a nozzle communicating with said suction-creating means through a connecting air passage and a port opening into said passage from the exterior of said casing, a converter member adapted to be inserted into said port for off-the-floor cleaning, supporting wheels for said casing, a bracket carrying the wheels remote from said nozzle and having a pivotal mounting on said casing, tension means acting on said bracket with sufficient 45 force to counterbalance the normal load on said last mentioned wheels but yieldable under an externally applied force acting to tilt said casing in a direction to raise the nozzle, said bracket having a portion thereof positioned adjacent said converter port and adapted to be shifted into positive latching engagement with said converter member after the same has been inserted into its port and the tilting pressure on said casing removed.
2. In a suction cleaner, the combination of a 50 casing including suction-creating means, a nozzle communicating with said suction-creating means through a connecting air passage, and a port opening into said passage from the exterior of said casing, a converter member adapted to be inserted into said port for off-the-floor cleaning, wheels supporting the casing at its forward and rear ends, a bracket pivotally mounted on said casing and carrying the rear supporting wheels, a spring 55 acting on said bracket to support the normal operating load but yieldable under pressure applied externally at the rear end of said casing to tilt the same in a direction to raise the nozzle, said bracket including a lever arm normally positioned to obstruct said port against the insertion of said converter member into its port but shiftable out of port obstructing position in the tilting movement of said casing to permit said converter member to be inserted and thence to be brought into positive latching engagement with a shoulder on said converter member when the tilting pressure on said casing is removed.
3. In a suction cleaner, the combination of a 60 casing including suction-creating means, a nozzle communicating with said suction-creating means through a connecting air passage and a port opening into said passage from the exterior of said casing, a converter member adapted to be inserted into said port for off-the-floor cleaning, supporting wheels at the forward and rear ends of said casing, a bracket pivotally mounted on the underside of said casing and carrying the rear supporting wheels, said bracket including a spring acting to counterbalance the normal load on said rear wheels but allowing the rear end of said casing to be depressed under an externally applied pressure to raise said nozzle, a lever arm carried by said bracket and normally positioned to obstruct said port against the insertion of said converter member but shiftable therefrom in the tilting of said casing to permit the insertion of said converter member into its port, said converter member having a shoulder adapted to be engaged by said lever arm upon the tilting of said casing in the opposite direction when the external pressure thereon is removed, thereby positively locking said converter member against removal.
4. In a suction cleaner, the combination of a 65 casing including suction-creating means, a nozzle communicating with said suction-creating means and a port adapted to receive a hose attaching member for converting the cleaner to off-the-floor cleaning operation, wheels mounted at the front and rear ends of said casing, a frame pivotally mounted on the underside of said casing and carrying the rear supporting wheels, a spring acting on said frame to counterbalance the normal load carried by said rear wheels, a manually operated adjusting device mounted on said casing and comprising a vertically shiftable stop member adapted to limit the pivotal movement of said casing in one direction about the axis of the front wheels but allowing it to pivot freely in the opposite direction, and a lever arm carried by said frame and adapted normally to obstruct said port but to be shifted from port-obstructing position to permit the insertion of said hose attaching member in the tilting of said casing either by said manually operated adjusting device or the application of a downward pressure on the rear end of said casing, said lever arm being subsequently adapted to contact said hose attaching member to hold said nozzle in raised position and to engage a projection on its underside to prevent its withdrawal from said port as said casing is allowed to tilt toward its normal position.
5. In a suction cleaner, the combination of a 70 casing including suction-creating means, a nozzle communicating with said suction-creating means and a port adapted to receive a hose attaching member for converting the cleaner to off-the-floor cleaning operation, wheels mounted at the

front and rear ends of said casing, a frame pivotally mounted on the underside of said casing and carrying the rear supporting wheels, springs acting at the pivotal mounting of said frame to 5 counterbalance the normal load carried by said rear wheels, a manually operated adjusting device mounted on said casing and comprising a vertically shiftable stop member adapted to limit the tilting movement of said casing about said 10 front wheels in a direction to lower said nozzle but allowing it to tilt freely in the opposite direction, and a lever arm carried by said frame and normally positioned to prevent said hose attaching member to be inserted in said port but 15 adapted to be shifted from port-obstructing position to permit the insertion of said attaching member in the tilting of said casing either by said manually operated adjusting device or the application of a downward pressure on the rear 20 end of said casing, said lever arm and hose attaching member subsequently coacting to retain said casing in tilted position with said nozzle elevated above the floor and said attaching member positively held against withdrawal from its 25 port upon the tilting of said casing in the opposite direction.

6. In a suction cleaner, the combination of a casing including suction-creating means, a nozzle at its forward end and communicating with said 20 suction-creating means through a connecting passage, a port leading into said passage from the exterior of said casing, a converter member adapted to be inserted into said port for off-the-floor cleaning, front and rear supporting wheels 25 mounted beneath said casing, the rear wheels being journaled on a frame comprising a hollow beam extending transversely beneath said casing and pivotally supported at its ends, a torsion spring enclosed within said beam and acting 30 thereon in a direction to overcome the load nor-

mally carried by said rear wheels, and a barrier lever extending at right angles from said beam and normally adapted to prevent the insertion of said converter member into said port, said frame being rotative by pressure exerted upon the 5 rear end of said casing to effect the raising of said nozzle and the shifting of said lever into a position to permit the insertion of said converter member.

7. In a suction cleaner, the combination of a 10 casing including suction-creating means, a nozzle at its forward end and communicating with said suction-creating means through a connecting passage, a port leading into said passage from the exterior of said casing, a converter member 15 adapted to be inserted into said port for off-the-floor cleaning, front and rear supporting wheels mounted beneath said casing, the rear wheels being journaled on a frame comprising a beam extending transversely beneath said casing, a 20 shaft extending lengthwise of said beam and fixed at its ends to said casing to form a pivotal mounting for said frame, torsion springs mounted on said shaft within said beam and acting on said frame to counterbalance the load normally 25 carried by said rear wheels, and a barrier lever extending forwardly at right angles from one end of said beam and normally positioned to prevent the insertion of said converter member into said 30 port, said frame being rotative by pressure exerted downwardly at the rear end of said casing thereby to raise said nozzle and to shift said barrier lever from port-obstructing position below said port to permit the insertion of said converter member, said barrier lever and converter member having coacting portions adapted 35 to lock positively said converter member against withdrawal from its port during converter operation.

BERNARD C. BECKER. 40
